UNITED STATES PATENT OFFICE.

FRANK L. ROSENTRETER, OF ROCHESTER, NEW YORK, ASSIGNOR TO THE CALDWELL MANUFACTURING COMPANY, OF SAME PLACE.

SASH-BALANCE.

SPECIFICATION forming part of Letters Patent No. 487,335, dated December 6, 1892.

Application filed March 16, 1892. Serial No. 425,195. (No model.)

To all whom it may concern.

Be it known that I, FRANK L. ROSENTRETER, of Rochester, in the county of Monroe and State of New York, have invented a certain 5 new and useful Improvement in Sash-Balances; and I do hereby declare that the following is a full, clear, and exact description of the same, reference being had to the drawings accompanying this specification.

10 My improvement relates to spring-balances; and it consists in the combination of a case having one side only, a drum fitted to said side and held by a rivet, a spring attached at one end to the drum and at the 15 other to a hub of the case, a tape winding on the drum, and a thin separate plate forming a brake fitted to the side of the drum opposite to the side plate of the case and held by the rivet, all as hereinafter more fully de- 20 scribed.

In the drawings, Figure 1 is a perspective view of the device. Fig. 2 is a sectional side elevation looking on the same side as in Fig. 1. Fig. 3 is a horizontal cross-section in line 25 *xx* of Figs. 1 and 2. Fig. 4 is a face view of the separate side plate.

A indicates the case, and B the drum. The case consists of the face-plate *a* and a single side plate *b*. The other side plate is not used; 30 but the drum is fitted to the single side plate, by which means the device is made thinner than usual and can be fitted more readily to narrow windows. The single side plate is made separate from the face-plate, and the 35 two are fitted together by a rivet at the top and an overlapping tongue at the bottom.

The drum *B* consists of a cylindrical rim with a closed face on the side opposite from the side plate of the case, and the drum and 40 case are united by a rivet *c*.

d is the ordinary flat coiled spring, inside the drum, one end being attached to the drum and the other to a hub *f* of the case, which projects inside of the drum.

45 *g* is the tape attached to the drum, winding on the same and supporting the sash. The drum is provided with a slot *h*, cut cross-wise in its rim, and the end of the tape is folded on itself, making an enlargement *k*.

50 The tape is simply slid into the slot, the enlargement resting under the rim. This makes a secure attachment and one not liable to break.

m is a thin plate fitted to the face of the drum on the side opposite from the closed 55 side of the case. It is preferably made of spring metal of the form shown in Fig. 4, the outer edge being made circular and projecting to the outer edge of the drum and the inner edge being made straight to fit closely to 60 the back of the face-plate *a*. By this means it corresponds in size and shape with the opposite fixed side of the case and covers the face of the drum and presents an appearance similar to the fixed side of the case, while at 65 the same time it serves as a spring and a brake, against which the drum rubs to produce tension on the sash. It is attached by the same rivet that unites the drum with the case, being provided with a central hole *n*, 70 through which the rivet passes. The spring-plate is prevented from turning by reason of its square edge fitting the face-plate. The face-plate on this side has a housing *p* at the edge, within which the spring-plate passes, 75 thereby making a good finish. It may, if desired, be made of different form from that above described, so long as it serves as a finish to the side of the device and a brake to the drum. 80

Having described my invention, I do not claim a case with one fixed side plate and a spring-disk set therein, as shown in my pending application, filed March 16, 1892, Serial No. 425,196. 85

What I claim as new, and desire to secure by Letters Patent, is—

In a sash-balance, the combination of a case having one side only, a drum fitted to said side and held by a rivet, a spring attached 90 to the drum and to the hub of the case for operating the drum, a tape winding on the drum, and a thin plate forming the brake to the drum and a cover to the side of the case opposite from the fixed side of the same, as 95 and for the purpose specified.

In witness whereof I have hereunto signed my name in the presence of two subscribing witnesses.

FRANK L. ROSENTRETER.
